ABSTRACT OF THE DISCLOSURE

A cylinder and dial knitting machine equipped with pattern wheels is described, which machine provides double the production and patterning capability of equivalent-sized prior art machines. Such features are brought about by the utilization, in such a pattern wheel machine, of two-butt cylinder needles, a first butt of each such needle being for selective engagement only with pattern wheels, and the second butt of each such needle being for engagement only with cams associated with each pattern wheel, the cams associated with each pattern wheel including a raise cam for placing the needles in such positions that the pattern wheel may eventually selectively operate on the respective first butts, a stitch cam for lowering needles as they move beyond the pattern wheel and a placer cam between the raise and stitch cams. Such practice permits the pattern wheels and associated cams to be packed around the periphery of the knitting machine, with attendant high cloth production and patterning versatility. The raise and placer cams are guarded to permit the machine to operate at higher speed with less attention and to thereby further increase productivity.

CROSS REFERENCE TO RELATED APPLICATIONS

Copending application Serial No. 670,097 filed Sept. 25, 1967 in the name of Lester Mishcon, now Patent No. 3,513,666, of which this application is a continuation-in-part.

BACKGROUND OF THE INVENTION**(1) Field of the invention**

The invention relates to improvements in and to independent needle cylinder and dial knitting machines, and in particular to improvements in and to such machines that employ slotted pattern wheels for the production of patterned cloth, such wheels being arranged in a predetermined manner with jacks for the selective actuation of the machine needles.

(2) Description of the prior art

Known prior cylinder and dial knitting machines are equipped with pattern wheels disposed in the manner depicted in United States Patent No. 2,006,821, issued July 21, 1935 (see in particular FIG. 4 thereof). Except for minor modifications thereto, the pattern wheel arrangement of United States Patent No. 2,006,821 is still employed today in cylinder and dial knitting machines manufactured by the instant assignee.

It had long been recognized that there is a practical limit to the number of pattern wheel cylinder feed stations that may be accommodated about a given diameter circular knitting machine. For example, with a 26-inch machine (i.e. cylinder diameter is 26 inches) and 2½ inch pattern wheels, the maximum number of feed stations thought to be possible was approximately 36 in

2

number, with each of the feed stations occupying approximately 3.14 inches of cylinder circumference. In such a machine, needles at each cylinder station are raised by a raise cam for eventual selective elevation by a pattern wheel. To pack more feed stations about the needle cylinder, thereby to increase cloth production on such machine, has heretofore meant, in effect, to sharpen the steepness of the cylinder raise cams, and of the pattern wheel raise angles. This however is impractical for the reason that the above noted machine already employs a cylinder cam raise angle of about 57 degrees, and a pattern wheel raise angle of about 35 degrees. To exceed about 57 degrees of cylinder cam raise angle is to encourage cylinder needle butt breakage; to exceed about 35 degrees of pattern wheel raise angle is to encourage jamming—and eventual breakage—of the cylinder needle butts within the pattern wheel slots, since such butts and slots cooperate like intermeshing gears, and therefore their respective pitches require control within close limits.

SUMMARY OF THE INVENTION

To avoid the impasse of a fixed number of pattern wheel feed stations about the cylinder of a cylinder and dial knitting machine equipped with pattern wheels, which machine is of a given diameter, and which impasse is brought about by practical limits on the raise angles of cylinder raise cams and pattern wheels, the present invention proposes the following:

Relocating the pattern wheels to their own cam free raceway; and utilizing two butts for needle raising purposes—one such butt being cooperative with the raise cams and the other such butt being cooperative, in tandem, with the pattern wheels, the butt which cooperates with the raise cams also being cooperative with stitch cams and with placer cams which are located between the raise and stitch cams.

Such a practice permits of acceptable cam and pattern wheel raise angles, say 57 degrees and 35 degrees respectively, but allows the formerly required 3.14 circumferential cylinder inches to be compressed to about 1.4 circumferential cylinder inches, thereby permitting of about 60 cylinder feed stations about a 26-inch machine (2½ inch pattern wheels), and permitting attendant about double the cloth production as has been heretofore possible with a cylinder and dial pattern wheel machine of equivalent diameter.

Aside from the matter of doubling cloth production, the invention also intrinsically provides the capability for greater patterning within the cloth so produced. That is, since machines incorporating the invention have a greater number of pattern wheels, than do equivalent-sized prior art machines, more pattern wheel slots are now available to influence any given cylinder needle during a single sweep of the needle cylinder, and hence pattern versatility is maximized.

In its preferred form, the invention utilizes two-butt cylinder needles, which admittedly are well known. In the relative travel of the cylinder needles with respect to a pattern wheel feed station, each lower needle butt initially meets a raise cam, which raises the cylinder needle relative to its corresponding slot in the pattern wheel in question, and its upper butt above the jack (if any) in such slot. Then the needle moves generally laterally for a time, without additional rise, and "during this time" the pattern wheel slot corresponding with such cylinder needle moves inwardly and upwardly and any jack in the slot engages the upper needle butt to position the cylinder needle in a well known manner.

The objects of the invention is to utilize more effectively the peripheral space about a cylinder and dial knitting machine provided with slotted pattern wheels,

whereby a greater number of cylinder feed stations than had heretofore been possible may be provided, and whereby cloth production by means of such a machine may be increased. As an added feature, the invention provides a cylinder pattern wheel cam section, dimensionally smaller than any heretofore known, which cylinder section includes an adjustable cam for use in selectively effectively disabling the needle-selection capability of the pattern wheel of such cylinder section.

The invention will be described with reference to the figures wherein:

FIG. 1 is a perspective view of cylinder and dial cam sections arranged according to the invention, and

FIG. 2 is a view of the apparatus of FIG. 1 taken generally along line 2—2 thereof.

With reference now to the figures, the means resulting in greater cloth production, and more versatility in patterning, will be described. Before proceeding with the description, however, it is well to realize that the view of FIG. 1 is generally from within the needle cylinder, looking past the cylinder and dial needle beds to the inner faces of the respective cam sections.

As is customary, a cylinder cam section 10 and a dial cam section 100 are arranged for cooperation with needles in, respectively, cylinder and dial needle beds, neither of which beds is shown for reasons of clarity, but both of which beds are provided with the usual needle accommodating slots. The cylinder section 10 is provided with an upper inclined face 14, and rotatably mounted to the inclined face 14, in the manner of copending application Ser. No. 670,097, now Patent No. 3,513,666, is a pattern wheel 24, such pattern wheel being held to such cylinder section 10 by means of a bolt 22 and nut 25 combination.

The pattern wheel 24 is rotatable in a plane parallel to the plane of its inclined face 14, and such plane forms an angle α with respect to the direction of relative travel of the cylinder needles 26. The pattern wheel 24 is provided with slots 28, skewed with respect to the plane of pattern wheel rotation; and the skewing and rotation plane are so chosen that the slots 28 may fully intermesh with the cylinder needles 26 when such slots 28 are vertically disposed and adjacent such needles. As above noted, it has been found that a pattern wheel rotation plane which makes an angle α , relative to the direction of cylinder needle travel, greater than about 35 degrees tends to bind and clog with needles, to the detriment not only of such cylinder needles, but of the pattern wheel itself. Each pattern wheel slot may—as is conventional—be filled with a high jack 30, or with a low jack 32, or with no jack depending on whether it is desired to raise a respective cylinder needle to knit, tuck or welt knitting height. A non-working portion of the pattern wheel extends beyond the cam section block 10 to overlie the plane of the working portion of a stitch cam 38 on another cam section block 10' when such another cam section block 10' is positioned adjacent the cam section block 10 (as shown in FIG. 2 and in the aforementioned copending application Ser. No. 670,097, now Patent No. 3,513,666) for prior use in actuating the needles 26.

The illustrated cam section 10 is provided with a needle raise cam 34 having a raise angle β of about 57 degrees (above noted to be about the steepest raise angle practical without causing needle butt damage) and the cylinder needles 26—which have respective upper and lower butts 27 and 29 respectively—are adapted to have their lower butts 29 ride up, and on, the raise cam 34. The lateral length d of the raise cam 34 is sufficiently short to permit each cylinder needle 26 to be sufficiently rapidly raised so that its respective upper butt 27 is above, in elevation, and waiting for the pattern wheel slot that it will eventually, and in tandem, mesh with as such slot relatively slowly comes inwardly and upwardly to meet and selectively raise the upper butt 27 of such cylinder needle.

After pattern wheel selection of the respective cylinder needles, such needles travel laterally of the cam section 10 to engage and be lowered by either a stitch draw cam 38 or a cam 40. In the event that a cylinder needle is raised by means of a high jack 30, such needle engages its stitch cam at, say, a level K; in the event a cylinder needle is raised by means of a low jack 32, such needle engages its stitch cam at, say, a level T; in the event a cylinder needle is not raised by means of a pattern wheel jack, such needle gets lowered to welt height by means of the cam 40, which cam 40 is compressible into the section 10, in well known manner, to prevent needle butt breakage caused by needles "flying" out of their respective welt paths.

The stitch draw cam 38 may be adjusted for stitch length determining purposes as indicated in copending application Ser. No. 670,097, now Patent No. 3,513,666, or as indicated in copending application Ser. No. 720,647, filed Apr. 11, 1968 in the name of Harry Agulnek and assigned to the instant assignee.

A manually settable placer cam 54, for use in canceling out all TUCK and WELT, or all WELT, selections of a given pattern wheel 24 is adapted to be cradled in a U-shaped cut-out 56, being positionable to wipe out all TUCK and WELT pattern wheel selections or to wipe out all WELT pattern wheel selections. The positioning of such cam 54, though not shown, may conventionally be by means of a pinion and ratchet, which pinion is on axis 58 and which ratchet is on the cam 54, as disclosed in Patent No. 3,513,666.

The dial cam section 100 which may be like the dial section of copending application Ser. No. 630,095, now Pat. No. 3,456,460, includes the usual system of cams 102 for cooperation with the dial needles 104; and by means of which dial cam section 100 in combination with the cylinder cam section 10 described above, rib and interlock cloth (depending on the machine gating) may be produced at a heretofore unattainable rate, and which combination of cylinder and dial cam sections 10, 100 is even more versatile as to patterning capability as was attainable with the machine of copending application Ser. No. 670,097. That is, not only is the patterning capability of the machine of application Ser. No. 670,097 intrinsic to the arrangement of the apparatus of FIGS. 1 and 2 but now, with such arrangement, knitting may be additionally influenced by means of the dial needles themselves.

The operation of apparatus incorporating the invention will be described, with special emphasis being placed on how the number of pattern wheel feed stations about the cylinder of a cylinder and dial knitting machine may be increased over equivalent prior art cylinder and dial knitting machines, whereby greater machine productivity and patterning versatility may be had. Shown in FIG. 1 are six two-butt latch type cylinder needles numbered 1 through 6, the upper butts 27 thereof having, in the description which follows, the suffixed T, and the lower butts 29 having the suffixed B. The cylinder needle 1 is shown first entering the cylinder cam section 10 with its lower butt 1B engaging the raise cam 34, at which time its corresponding pattern wheel slot, i.e. the one having high jack 30', is sufficiently apart from and below the upper needle butt 1T that the jack and upper needle butt do not engage. The cam 34, then, relatively rapidly (i.e. compared with the rise of the pattern wheel slot in question) drives the cylinder needle upwardly so that the needle assumes the position of the cylinder needle 2, the lower butt 2B of such cylinder needle 2 riding almost to the apex of the raise cam 34, with the upper butt 2T thereof in its corresponding pattern wheel slot (as shown) or above such slot (depending upon the angular difference between the raise cam and pattern wheel), but in any event with the butt 2T above the jack (if any) in the slot. The cam 34 then releases the lower needle butt 2B and, as the needle cylinder carries

the cylinder needle 2 laterally of the cylinder section 10 to the position occupied by the cylinder needle 3, the pattern wheel slot corresponding with such cylinder needle, moves to cause the jack therein to come up to engage the underside of upper needle butt 3T. With no 5 jack in the pattern wheel slot corresponding with a given cylinder needle, the needle passes along like the needle 4, the upper butt 4T slipping out of its pattern wheel slot as such slot moves up and away from the upper needle butt 4T, the lower butt 4B thereof ultimately engaging 10 the cam 40 and being lowered thereby to welt height; with a high jack in the pattern wheel slot corresponding with a given cylinder needle, the needle gets carried upwardly by means of its upper butt, and passes along like the cylinder needle 5 (the lower butt 5B riding just beneath a guard cam 70 until it meets and is lowered by the stitch cam 38) whereby such needle cooperates with its corresponding dial needle 104 to knit, say an interlock stitch; similarly, a low jack in the pattern wheel slot corresponding with a given cylinder needle causes 20 such needle to pass along at tuck height like the cylinder needle 6, the lower needle butt 6B being lowered by the cam 38 as the upper butt 6T of such needle slips out of its corresponding pattern wheel slot, whereby such needle cooperates with its corresponding dial needle 104 to knit, 25 say a cardigan stitch. Guard cam 70 restricts the uncontrolled upward movement of needles from the raise and placer cams.

While the invention has been described in its preferred form it is to be understood that the words which have 30 been used are words of description rather than of limitation, and that changes within the purview of the appended claims may be made without departing from the true scope and spirit of the invention, bearing in mind that the key to the invention is the use, in a pattern 35 wheel circulation knitting machine, of one needle butt for actuation only by cams, and the use of a second needle butt for actuation only by pattern wheels.

Having thus set forth the nature of this invention, what is claimed herein is:

1. Circular knitting apparatus comprising:
  - (a) a first plurality of needles, which needles are provided with lower and upper butts,
  - (b) a second plurality of needles cooperative with said first plurality of needles,
  - (c) a cylinder cam section block (10) for use in actuating the needles of said first plurality of needles,
  - (d) a slotted pattern wheel angularly disposed relative to the vertical axis of said cylinder section block

(10) and adapted to have its periphery cooperative with only the upper butts of the needles in said first plurality thereof for selectively raising the same, said pattern wheel having a non-working portion extending beyond said cylinder cam section block (10) to overlie the plane of the working portion of a stitch cam on another cylinder cam section block (10') when such another cam section block (10') is adjacent the first mentioned cam section block (10) and in a position for cams thereon to actuate the needles in advance of cams on the first mentioned cam section block (10),

- (e) a raise cam for the cam section block (10) adapted to cooperate with only the lower butts of the needles in said first plurality thereof, said raise cam being disposed in advance of the effective periphery of said pattern wheel in the direction of relative needle travel,
- (f) a stitch cam for the cam section block adapted to engage only said lower butts of the needles in said first plurality to lower same to set stitches selected by said pattern wheel, a placer cam on the cam section block (10) between the raise cam and stitch cam, said placer cam being adapted to engage only said lower needle butts,
- (g) a guard cam for the cam section block (10) disposed to restrict the upward movement of knitting needles from the raise cam and placer cam, and
- (h) a dial cam section block for use in selectively actuating the needles of said second plurality of needles.

2. The apparatus of claim 1 wherein said placer cam is adapted for vertical positioning relative to said pattern wheel.
